UNITED STATES PATENT OFFICE

92,636

DESIGN FOR AN ELECTRIC LIGHTING FIXTURE

Marshall S. Wideroe, Chicago, Ill., assignor to
Benjamin Electric Mfg. Company, Des Plaines,
Ill., a corporation of Illinois

Application April 25, 1934, Serial No. 51,509

Term of patent 14 years

To all whom it may concern:

Be it known, that I, MARSHALL S. WIDEROE, a citizen of the United States, residing at Chicago, in the county of Cook, and State of Illinois, have invented a new, original, and ornamental Design for an Electric Lighting Fixture, of which the following is a specification, reference being had to the accompanying drawing, forming a part thereof.

The figure is a perspective view of the lighting fixture showing my new design.

I claim:

The ornamental design for an electric lighting fixture, substantially as shown.

MARSHALL S. WIDEROE.
